SAFETY THREAD CUTTER FOR SEWING MACHINES

Anna C. Silverman, Brooklyn, N. Y., assignor of one-half to Milton D. Silverman, New York, N. Y.

Application November 23, 1942, Serial No. 466,546

10 Claims. (Cl. 30—290)

This invention relates to new and useful improvements in a safety thread cutter for sewing machines.

More specifically, the invention proposes the construction of a safety thread cutter adapted to be mounted upon the pressure foot of a sewing machine or in close proximity thereto in a manner to permit the threads to be severed at the end of a sewing operation without requiring that the operator handle a pair of scissors or cutting implement to accomplish the cutting operation.

Still further, it is proposed to characterize the thread cutter by a shield having an edge cutout and a blade supported within a groove formed in one face of the shield and having a portion of its cutting edge aligned with and extended across the edge cutout for cutting threads engaged into the edge cutout.

Another object of the invention proposes to provide the shield with sloping sides converging on the edge cutout in a manner to direct threads to be cut into the edge cutout to be engaged by the cutting edge of the blade.

A further object of this invention proposes to adjustably mount the cutting blade upon the shield in such a manner that the blade may be shifted relative to the shield to align a new sharp portion of the cutting edge of the blade with the edge cutout when the portion being used becomes dull.

A still further object of this invention proposes the provision of a novel mechanical means for moving the cutting blade relative to the shield in a manner to change the exposed portion of the cutting edge relative to the edge cutout.

It is a further object of this invention to provide a safety thread cutter for sewing machines which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a portion of a pressure foot of a sewing machine having a thread cutter constructed in accordance with this invention.

Fig. 2 is a perspective view of the shield of the thread cutter per se.

Fig. 3 is a perspective view of the blade of the cutter per se.

Fig. 4 is a side elevational view of a portion of a pressure foot of a sewing machine having a thread cutter constructed in accordance with a modification of this invention.

Fig. 5 is a horizontal sectional view taken on the line 5—5 of Fig. 4.

Fig. 6 is a vertical sectional view taken on the line 6—6 of Fig. 4.

Fig. 7 is a view similar to a portion of Fig. 4 but illustrating a still further modification of the invention.

Fig. 8 is a vertical sectional view taken substantially on the line 8—8 of Fig. 7.

Fig. 9 is a side elevational view similar to Fig. 4 but illustrating a still further modification of the invention.

Fig. 10 is a horizontal sectional view taken on the line 10—10 of Fig. 9.

Fig. 11 is a view similar to Fig. 7 but illustrating still another modification of the invention.

Fig. 12 is a partial horizontal sectional view taken on the line 12—12 of Fig. 11.

Fig. 13 is a vertical sectional view taken on the line 13—13 of Fig. 11.

Fig. 14 is a perspective view per se of the cutting blade used in the last modification of the invention.

The safety thread cutter for sewing machines, according to this invention, includes a shield 10 having an edge cutout 11 with sloping sides 12 and 13 converging on the edge cutout 11. The shield is constructed of metal and is adapted to be mounted on the side of a pressure foot 14 of a sewing machine, as will be hereinafter described, with its edge cutout 11 disposed to the rear of the pressure foot 14.

The inner face of the shield 10 is formed with a vertical groove 15 forming spaced shoulders which are adapted to engage opposite sides of the pressure foot 14 for holding the shield against horizontal movement on the pressure foot. The shield 10 is further formed with an opening 16 through which a screw 17 is adapted to be passed. The screw is adapted to be engaged with a complementary opening formed in the side of the pressure foot 14 and cooperates with the groove 15 in holding the shield 10 in position upon the pressure foot.

The inner face of the shield 10 is also formed with a horizontal groove 18 which extends across the vertical groove 15 and the edge cutout 11. A blade 19 having a top cutting edge 20 is adapted to be disposed within the groove 18 with a portion of its cutting edge 20 exposed at the edge cutout 11 to cut threads engaged into the edge cutout. The

blade 19 is also formed with a horizontal slot 21 through which the screw 17 is adapted to pass and which permits the blade to be shifted relative to the shield 10 for aligning a new portion of its cutting edge 20 with the edge cutout 11. When the screw 17 is tightened into position the blade 19 is clamped in position between the adjacent faces of the shield 10 and the pressure foot 14.

The manner of using the thread cutter is as follows:

With the thread cutter mounted upon the pressure foot 14 as shown in Fig. 1 it is an easy matter to cut threads on a piece of cloth upon which a sewing operation has just been completed. It is merely necessary to take the article from beneath the pressure foot and loop the threads over the top of the shield and move them downwards. The sloping sides 12 and 13 will direct the threads into the edge cutout and 20 direct the threads into the edge cutout and 20 against the cutting edge 20 of the blade to be cut thereby.

In the event the exposed portion of the cutting edge 20 of the cutting blade 19 becomes dull it is merely necessary to loosen the screw 17 25 slightly to free the cutting blade 19 to be shifted horizontally relative to the edge cutout 11 to align another portion of the cutting edge 20 with the edge cutout 11. Retightening the screw 17 will clamp the blade in its new position.

In the modification of the invention shown in Figs. 4 to 6 the construction of the thread cutter is similar to that previously described differing merely in the shape of the shield 10' and the cutting blade 19'. In this form of the invention the shield 10' is substantially rectangular and the cutting blade 19' is rectangular.

In other respects this form of the invention is similar to the previous forms and like reference numerals identify like parts in each of the several views.

In Figs. 7 and 8 the shield 10'' is formed with spaced spring clips 22 which engage over the bottom portion of the cutting blade 19'' for holding it in position with a portion of its cutting edge 20 aligned with the edge cutout 11. To move the cutting blade 19'' relative to the shield 10'' to align sharper portions of the cutting edge 20 with the edge cutout 11 it is merely necessary to slide the blade 19'' in the clips 22.

In other respects this form of the invention is also similar to the previous form.

In Figs. 9 and 10 provision is made for permitting the cutting blade 19''' to be shifted vertically relative to the shield 10''' for permitting the top cutting edge 20 of the blade to be aligned with the edge cutout as the top cutting edge becomes worn away when the edge is ground to renew the cutting edge.

To accomplish this both the groove 18' in the shield 10''' and the slot 21' in the cutting blade 19''' are arranged vertically so that the blade will be slid vertically in the loosened position of the screw 17.

In other respects this form of the invention is also similar to the previous form.

In Figs. 11 to 14 another modification of the invention is shown which is characterized by a shield 30 having an edge cutout 31 from which converging sloping sides 32 and 33 extend for directing threads into the edge cutout. The shield 30 is adapted to be mounted upon the side of a pressure foot 34 of a sewing machine with its edge cutout 31 directed to the rear thereof.

The inner face of the shield 30 is formed with

a horizontal groove 35 within which a blade slide 36 is disposed. A cutting blade 37 is mounted upon the top edge of the blade slide 36 by means of rivets 38. The cutting blade 37 is mounted upon the blade slide 36 in such a manner that a portion of its cutting edge 39 will extend across the edge cutout 31 to cut threads engaged into the edge cutout.

Mechanical means is provided for permitting the blade slide 36 to be shifted relative to the shield 30 to align a fresh portion of the cutting edge 39 of the cutting blade 37 with the edge cutout 31. This means is characterized by a bushing 40 rotatively extended through an opening 41 formed in the shield 30. The outer end of the bushing 40 is formed with an enlarged knob 42 by which the bushing 40 may be conveniently turned. The inner end of the bushing 40 is formed with a small pinion 43 disposed within a horizontal elongated slot 44 formed in the slide 36. The pinion 43 meshes with rack teeth 45 formed along the bottom edge of the slot 44. Thus by turning the knob 42 which in turn turns the bushing 40 and the pinion 43 the blade slide 36 may be moved to the right or the left to similarly move the blade 37 and align a new portion of its cutting edge 39 with the edge cutout 31.

Means is provided for mounting the shield 30 upon the side of the pressure foot 34 and for locking the bushing 40 against being rotated. This means comprises a screw 46 which passes through the bushing 40, the slot 44 and threadedly engages a complementary opening 47 formed in the side of the pressure foot 34. Tightening the screw 46 will clamp the slide against the side of the pressure foot 34 and hold the bushing 40 against moving to hold the blade slide 36 in its various adjusted positions relative to said slide.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A safety thread cutter for sewing machines, comprising a shield having an edge cutout formed with sloping sides, means for attaching said shield on a pressure foot of a sewing machine or other part, a groove on the back of said shield and extending across said edge cutout, and a blade adjustably supported in said groove and extending across said edge cutout.

2. A safety thread cutter, comprising a shield having an edge cutout formed with sloping sides, means for attaching said shield on a fixed support, a groove on the back of said shield and extending across said edge cutout, and a blade adjustably supported in said groove and extending across said edge cutout, said means, comprising, a screw engaged through said shield and engaging a complementary opening in said support.

3. A safety thread cutter, comprising a shield having an edge cutout formed with sloping sides, means for attaching said shield on a fixed support, a groove on the back of said shield and extending across said edge cutout, and a blade adjustably supported in said groove and extending across said edge cutout, said means, comprising, a screw engaged through said shield and engag-

ing a complementary opening in said support, said shield being formed with a vertical groove forming spaced shoulders for engaging the sides of said support to hold said shield against turning relative to said support about said screw.

4. A safety thread cutter for sewing machines, comprising a shield having an edge cutout formed with sloping sides, means for attaching said shield on a pressure foot of a sewing machine or other part, a groove on the back of said shield and extending across said edge cutout, and a blade adjustably supported in said groove and extending across said edge cutout, said blade having a portion of its cutting edge extended across said edge cutout.

5. A safety thread cutter for sewing machines, comprising a shield having an edge cutout formed with sloping sides, means for attaching said shield on a pressure foot of a sewing machine or other part, a groove on the back of said shield and extending across said edge cutout, and a blade adjustably supported in said groove and extending across said edge cutout, said blade being adjustable horizontally to have new areas of its cutting edge aligned with said edge cutout when the area being used becomes dull.

6. A safety thread cutter for sewing machines, comprising a shield having an edge cutout formed with sloping sides, means for attaching said shield on a pressure foot of a sewing machine or other part, a groove on the back of said shield and extending across said edge cutout, and a blade adjustably supported in said groove and extending across said edge cutout, said blade being adjustable vertically to permit its top cutting edge to be aligned with said edge cutout as said top edge is worn away when the blade is ground to renew said cutting edge.

7. A safety thread cutter for sewing machines, comprising a shield having an edge cutout formed with sloping sides, means for attaching said shield on a pressure foot of a sewing ma-

chine or other part, a blade positioned at the back of said shield and extending across said edge cutout, and clips for holding said cutting blade in position on said shield.

5 8. A safety thread cutter for sewing machines, comprising a shield having an edge cutout formed with sloping sides, means for attaching said shield on a pressure foot of a sewing machine or other part, a groove on the back of said shield and 10 extending across said edge cutout, and a blade adjustably supported in said groove and extending across said edge cutout, said blade being mounted upon a blade slide, and means for moving said blade slide relative to said shield to align new areas of said cutting blade with said edge cutout.

9. A safety thread cutter for sewing machines, comprising a shield having an edge cutout formed with sloping sides, means for attaching said shield 20 on a pressure foot of a sewing machine or other part, a groove on the back of said shield and extending across said edge cutout, and a blade adjustably supported in said groove and extending across said edge cutout, said blade being mounted 25 upon a blade slide, and means for moving said blade slide relative to said shield to align new areas of said cutting blade with said edge cutout, said latter means, comprising a turnable bushing formed with a small pinion disposed with a slot 30 formed in said blade slide and meshing with teeth formed along the bottom edge of said slot.

10. A safety thread cutter for sewing machines, comprising a shield having an edge cutout formed with sloping sides, means for attaching said shield on a pressure foot of a sewing machine or other part, a blade positioned behind said shield with an area of its cutting edge extending across said edge cutout, and means supporting said blade on said shield to be shiftable 35 relative to said shield to vary the aligned position of the cutting edge with said edge cutout.

ANNA C. SILVERMAN.
